United States Patent Office.

JOSEPH LINNESS, OF CHICAGO, ILLINOIS.

Letters Patent No. 75,556, dated March 17, 1868; antedated February 28, 1868.

IMPROVED WINDOW-SASH.

The Schedule referred to in these Letters Patent and making part of the same.

TO ALL WHOM IT MAY CONCERN:

Be it known that I, JOSEPH LINNESS, of the city of Chicago, in the county of Cook, and State of Illinois, have invented an Improved Sash, and with it an improved method of setting glass therein; and I do declare that the following is a full, clear, and exact description of the construction and operation of the same, reference being had to the accompanying drawings, and the letters marked thereon, making a part of this description, in which—

Figure 1 represents an elevation of the sash complete, with the glass set.

Figure 2 represents a section, taken through the place indicated by the line X X in fig. 1.

Figure 3 represents an elevation of the outside section of the bars and mullions, (termed filling,) the same being an inside view, detached from the sash-frame.

Figure 4 represents a broken elevation of the inside of one of the stiles or rails.

Figure 5 represents an elevation of one of the side strips, used to bind the glass between the rubber linings in the rabbet of the frame, also detached.

The nature of my invention consists in having the filling of the sash made in two parts or sections each, and so arranging them with corresponding strips that the glass may be firmly clamped and bound between the two linings of rubber or other suitable material, by means of screws or other fastenings, and constructing the inner section of the filling so that the several parts surrounding either pane of glass may be easily removed for purposes of repair, without disturbing the rest of the filling or the joints of the sash-frame, and to admit broken glass to be replaced with equal facility, while the two faces of the sash being of solid wood or metal, and clamped as described, all the fastenings being on the inside of the sash, it is stronger than the ordinary sash, as now made, and more secure from burglars.

It is well known that putty dries up, and very often cracks and falls off, leaving a free passage for air and water to pass round the edge of the glass, and in other cases it will cement or adhere so closely to the glass and wood, as to cause the glass to sustain nearly or quite the same jar as the sash, frequently causing breakage.

I am aware of the fact that elastic and flexible material has been used as packing, in connection with glass and other substances, in matters of science and for medical instruments.

In order to give a correct understanding of my device, I have marked corresponding parts with similar letters and figures, and will now proceed to give a detailed description of the drawings.

Letter A represents the stiles and rails of the sash-frame, having suitable rabbets for receiving and holding the glass, C, and other surroundings, as shown by section of rail in fig. 2, and section of stile, fig. 4. They also have gains, letter G, in fig. 4, cut or crossed, to correspond with the outside section of filling, the ends of which are received in the said gains G by slipping down or in square from the inside of the rabbet. It may be seen, from the drawings, that the filling cannot be removed from the sash-frame on the outside without cutting or breaking it, but that it may be readily removed on the inside. The strips D have their ends bevelled or coped to fit the bevel or moulding of the bars and mullions, so that when screwed down they hold the filling as well as the glass securely in place.

When desired, for resetting glass or other repairing, without taking the sash-frame apart, as is very frequently needed in sash made in the ordinary way, the outside section of filling is secured at the intersections, by means of a metallic plate or plates, sunk in the wood and fastened by screws or other fastenings, when wood is used, or its equivalent where metal filling is used. The outside section of filling being placed in position in the frame, the whole is ready to receive the first or outside rubber linings, which may be cemented or fastened to the frame and filling, or not, as thought best. We next proceed to place the glass in position, then the inside linings, (if loose,) and lastly the inside section of the filling, with the corresponding strips, which have been previously fitted and prepared either with or without the inside linings cemented to them. The two sections of filling are now drawn together and clamped, by means of the screws with the glass and rubber linings between them, and lastly the strips are placed in the rabbets, and pressed firmly down in position, until the screws have been entered through them into the stiles and rails, when the whole is secured in place, and may be cleaned off to present an even surface at all the joints. Where it is desirable to have ornamental sash, screws with plated heads, or raised and plated can be used with advantage. In ordinary sash, common screws sunk and painted over may answer.

Letters *a*, in fig. 2, represent the rubber linings upon both surfaces and at the edge of the glass in the rabbet of the frame, which linings extend completely around each pane of glass. In addition to these linings, and in combination with them for store-fronts, and other places where heavy panes of glass are used, I place under and over the edges or ends of the glass, and, if needed, at the sides also, rubber cushions or springs. The object of these is to prevent breakage of valuable panes of glass, by vertical or lateral pressure, from the settling of walls and other causes.

It will be obvious, from an examination of this description and the drawings, that the bars, mullions, and strips can be removed from either pane of glass separately, on the inside of the sash, and broken glass replaced, and the filling put back, by any person of ordinary intelligence.

It is also obvious that, where a single pane of glass is used, it is only necessary to use the strips in combination with the rubber linings, as described, and I claim these rubber linings, as specified, which will be found useful in show-cases, looking-glass frames, picture-frames, dressing-cases, and similar purposes, as well as in rail-cars, omnibuses, stage-coaches, and steamboats.

Having thus fully described my invention, I proceed to state my claims.

What I claim as my invention, and desire to secure by Letters Patent, is—

1. Construction of a sash, with a filling of bars and mullions, with a removable outer section, I F, and a removable inner section, E D, so that one or both may be removed without disturbing the frame, substantially as specified.

2. The cross-bar or plate H, when placed across the intersection of the bars and mullions on the inside, so as to be concealed when the sash is put together, substantially as shown.

3. The method of securing the removable bars and mullions in the frame, by means of the strips D, made with bevelled or coped ends, to fit over the corresponding bevel or moulding of the bars and mullions, substantially as specified.

JOSEPH LINESS.
